DOOR FRAMES

Julius A. Steffan, 2633 Endicott, Overland, Mo., and Joseph L. Williams, 485 E. Adams, Kirkwood, Mo.; Marie M. Steffan, administratrix of said Julius A. Steffan, deceased
Filed Jan. 31, 1962, Ser. No. 170,040
1 Claim. (Cl. 189—46)

This invention relates to door frames of the kind in which head and jamb members are mounted on and inboard of a fixed frame.

One of the objects of this invention is to provide a door frame in which head and jamb members are constructed to be quickly and easily installed, which form neat, clean, tight, meeting joints with one another, and which tend to maintain their relative positions with respect to one another, in spite of dimensional changes in the fixed frame.

Other objects will become apparent to those skilled in the art in the light of the following description and accompanying drawing.

In accordance with this invention, generally stated, an improved sectional door frame is provided in which head and jamb members, mounted on, and inboard of a fixed frame, are continuously biased into tight engagement by resilient biasing means supported by at least one of said members, and stop-guide means are provided on one or more of the members, which guide and limit the movement of the jamb members in response to the bias, and position the members in a fixed relationship with one another.

In the drawing:

FIGURE 1 is a view in front elevation of a complete door frame constructed in accordance with this invention;

FIGURE 2 is a view in front elevation of the finish frame in the process of erection;

FIGURE 3 is a fragmentary detail view in front elevation, partly in section, showing one embodiment of finish frame members of this invention;

FIGURE 4 is a fragmentary detail view in front elevation, showing the finish frame members of FIGURE 3 in assembled relation;

FIGURE 5 is a sectional view taken along the line 5—5 of FIGURE 1;

FIGURE 6 is a fragmentary view in perspective of the upper end of a jamb section of the embodiment of finish jambs shown in FIGURES 3—5, without the spring of that embodiment;

FIGURE 7 is a fragmentary view in front elevation showing another embodiment of finish frame of this invention; and

FIGURE 8 is a fragmentary view in side elevation, partly broken away of still another embodiment of this invention, wherein two springs are utilized.

Referring now to the drawing for illustrative embodiments of this invention, and particularly to FIGURES 1—6, reference numeral 1 indicates a rough buck or fixed frame, on which a sectional finish frame 10 of this invention is mounted. The rough buck 1 is made up of two stiles 2 and a buck head 3. In the embodiment shown, plaster board 4 is nailed to the side faces of the rough buck before the finish frame is mounted, and the finish frame is mounted over the plaster board, but this arrangement is not a part of the invention, it being immaterial thereto whether the finish frame is designed for dry-wall or plaster. In this embodiment, the sectional finish frame is made up of a hinge side jamb member 5, a strike plate side jamb member 6, and a header member 7.

Each of the jamb members 5 and 6, is provided with a mitered bearing surface 8 at its upper end. In the embodiment shown, each of the jamb sections 5 and 6 is provided with a central door stop 11 having a plane

2

transverse panel 12 and stop faces 13, and with side webs 14, connected, on either side of the stop, to the stop faces 13.

Both of the jamb sections 5 and 6 are provided with 5 stop-guide lugs 15, which, in the embodiment shown, are simply tabs, one end of which is struck from a side web 14, and the other end of which is integral with the side web. In this embodiment, the strike plate side jamb member 6 is provided, in the panel 12 of the stop, with a slot 20. Actually, both jamb members can be provided with slots 20, but the slot 20 on the hinge side serves no function.

A strong, semi-elliptical spring 25 is mounted on the (hidden) rough buck side of the panel 12 of the strike 10 plate side jamb member 6. The vertically upper end of the spring 25 has a dog leg 26, the free end of which extends through the slot 20 and lies along and against the panel 12 above the slot as shown in FIGURE 3. The lower end of the spring 25 is curved away from the panel 12, toward the rough buck, so as to provide a smooth bearing surface 27 against the panel 12. The bowed section of the spring 25 is spaced from the stop panel 12 a distance greater than the greatest anticipated distance between the stile 2 of the rough buck and the panel 12, when 15 the finish frame is installed. Thus, when the frame is installed, the spring 25 will be compressed between the stile 2 and the panel 12 of the jamb 6 as shown in FIGURE 4.

The header 7 has a stop 31 and side webs 34, and is 20 provided at both of its ends with a mitered bearing surface 28, complementary to the mitered bearing surface 8 on the upper ends of the jamb members 5 and 6. The header is cut away at its two ends in such a way as to 25 make a tight joint with the upper end of each of the jamb members, when the header is properly positioned with respect to the jamb members.

The proper positioning of the header with respect to the jamb members is accomplished by a cooperation between the spring 25, compressed between the fixed frame 30 and jamb member 6, bearing surfaces 8 and 28, and stops 15, engaging the header 7. It can be seen that, when the mitered bearing surfaces 8 and 28 of the jamb member and header, respectively, are in engagement, a force exerted on the jamb member in a direction away from the 35 rough buck, will tend to cam the header upwardly. If the header is initially positioned vertically below the stops 15, the header will move up until the stops 15 engage the hidden face of the side webs 34, as shown in FIGURE 4, whereupon the header will be securely held in position, being anchored against upward displacement by the stops, and effectively prevented from downward displacement by the bias of the spring 25, acting through the camming surfaces 8 and 28.

As is explained hereafter, the hinge side jamb member 5 is fixedly mounted on the stile opposite the strike plate side jamb member, so that the thrust of the spring 25 against the strike plate side jamb section 6, hence the header 7, in a direction toward the hinge side jamb member, also causes the header 7 to cam upwardly on the 45 mitered section 8 of the hinge side jamb member 5, until the stops 15 on the hinge side jamb member engage the hidden surface of the side webs 34 of the header, so that both ends of the header are properly positioned and tightly maintained by the spring 25.

In the installation of a finish frame of this embodiment, assuming that the rough buck is already in place, the hinge side jamb member 5 is lined up heightwise and plumbed and fastened securely to one of the stiles 2. The header 7 is then put into place with a part of the bearing surface 70 28 in contact with the bearing surface 8 of the hinge side jamb member, but with the side webs 34 below the stops 15 of the hinge side jamb member. Strike plate side jamb

member 6 is initially positioned with its lower end away from the stile on which it is to be mounted, and with its upper end against and embracing the stile as shown in FIGURE 2. The header 7 also tends away from the buck head 3, at the end of the header to be engaged by the end of the strike plate side jamb member 6. The mitered bearing surface 8 of the latter is partly in contact with the outer end of the mitered bearing surface 28 on the header, and the side webs 34 of the header are below the stops 15 on the strike plate side jamb member 6.

The lower end of the jamb member 6 is now moved toward its stile, and the jamb member 6 and header 7 are moved upwardly against the bias of the spring 25. The spring 25 has its smooth bearing surface 29 in contact with the stile 2, so that, in spite of the stiffness of the spring, the jamb member 6 and header 7 can be pushed by one man into position. When the joint between the mitered bearing surfaces at the upper end of the hinge side jamb member is tight and clean, the header and jamb member 5 are at right angles to one another. The lower end of the jamb member 6 is now moved transversely until its upper mitered corner with the header is also tight and clean, and the jamb member 6 is finally mounted on the stile 2 by means of a nail driven, through a strap 35 on the bottom of the jamb member 6, into the stile 2. Any other suitable securing means may, of course, be used instead of a nail.

Another embodiment of this invention is shown in FIGURE 7. In this embodiment, a spring 50 is secured at each end of the header 7. The spring 50 is curved through more than 90°, so that, in its unconfined position indicated as 50', the free end of the spring extends beneath the stop 31. In this embodiment, in which the spring is positioned within the channel defined by the stop 31, it can be seen that a space for the free end of the spring is automatically provided between the rough buck and the corresponding stop of the jamb section.

The installation of the finish frame of this embodiment is substantially the same as that of the first embodiment shown. The hinge side jamb member 5 is securely mounted first, and the header is positioned with the spring 50 in the channel defined by the stop on each of the jamb sections, and with the side webs of the header below the lugs on the upper ends of the jamb sections. The strike plate side jamb member 6 is then pushed up into place, and the force of the springs 50, tending to pull the jamb sections inwardly with respect to the head section, causes the head section to cam upwardly until the stop-guide lugs 15 engage the hidden side of the side webs and the header.

The lower end of the strike-plate side jamb member 6 is then nailed or otherwise secured in position.

The embodiment shown in FIGURE 8 is the present commercial embodiment. In it, two springs, 85, each with an integral U-shaped clip 87 at its upper end, are clipped to the upper edge of the side webs 14 immediately adjacent and on opposite sides of the door stop 11.

The installation of the finish frame of the embodiment shown in FIGURE 8 is exactly the same as that of the embodiment shown in FIGURES 1-6.

Numerous variations in the construction of the door frame assembly of this invention will occur to those skilled in the art in the light of the foregoing disclosure. For example, other resilient means besides a spring, may be employed to bias the frame sections together resiliently, and to keep them positioned in spite of deformation of the rough buck. For example, an inflatable bag of elastic material such as rubber or plastic can be positioned behind the strike plate side jamb member, and inflated either before or after the installation of the frame. A spring can be mounted by one of its ends on the rough buck, rather than on the finish frame members, although the latter arrangement has many advantages, and, as indicated, is preferred. A plurality of springs may be employed in each of the areas where a single spring has been shown.

Having thus described the invention, what is claimed and desired to be secured by Letters Patent is:

In a door finish frame in which header and jamb members are mounted on, inboard of and in embracing relation to a fixed frame, the improvement comprising mitered complementary bearing surfaces on the meeting ends of a jamb and header member, a semi-elliptical spring with its center section forming a smooth bearing surface contiguous the fixed frame and having a dog-leg at its upper end, said jamb member having near its said meeting end a slot, through which said dog-leg extends releasably to hold said spring, and stop-guide means on said jamb member near said meeting end but below said slot.
